Inventor:

Hammond V. Hayes.

UNITED STATES PATENT OFFICE.

HAMMOND V. HAYES, OF CAMBRIDGE, MASSACHUSETTS.

TELEPHONE-TRANSMITTER.

SPECIFICATION forming part of Letters Patent No. 377,612, dated February 7, 1888.

Application filed September 5, 1887. Serial No. 248,826. (No model.)

To all whom it may concern:

Be it known that I, HAMMOND V. HAYES, residing at Cambridge, in the county of Middlesex and State of Massachusetts, have invented 5 certain Improvements in Telephone-Transmitters, of which the following is a specification.

This invention relates to telephone-transmitters which are employed in connection with a battery, and which operate to vary the resistance of, and consequently the current flowing in, the battery-circuit. It has more particular reference to that class of battery transmitters in which granular particles of conducting material, and specially of carbon, constitute the 10 current-varying medium, they being confined in a loose and free state between two conducting-plates, which are thereby electrically connected, both of the said plates being included in the circuit of the battery. Heretofore such 15 transmitters have uniformly been rigidly mounted either on a diaphragm or on a separate support, and in the latter case one of the electrodes or plates thereof has been mounted upon or has itself constituted the vibrating 20 diaphragm.

My invention consists in providing two complete and independent current-varying organisms of the type described above, each being separately mounted on a spring-support and 25 adjustable independently of each other, and both being in contact with and adapted to operate in association with a single complementary or opposing electrode, which latter is vibrated by and in accordance with the vibrations of the diaphragm and is adjustable with 30 respect thereto, so that each full vibration of the said diaphragm is caused to effect a substantially equal but opposite change in both current-varyers, the resistance of one being 35 increased at the same moment when the resistance of the other is decreased, and vice versa, said diaphragm and electrodes being combined with an induction-coil having a double and differentially-wound primary helix 40 whose wires are in circuit one with each of the spring-supported electrodes, and both with the diaphragm-electrode, all as hereinafter set forth.

The object of my invention is, generally, to 45 produce a transmitting-telephone of improved

efficiency, and to utilize to the fullest extent the variations of resistance produced in its operation.

In the drawings which accompany and illustrate this specification, Figure 1 is an elevation of the instrument inclosed in a suitable case, with the cover and working parts partly in section and showing the circuits. Fig. 2 is a horizontal section of the same, but with the circuits and induction-coil superadded, in a 55 conventional diagram. Fig. 3 is a view in section of the compound granulation-holding buttons enlarged.

A is the transmitter-case, formed upon the plan of the well-known Blake transmitter, 65 (the external form is, however, immaterial,) and B is the cover thereof, having, as usual, a recessed aperture, I, to serve as a mouth-piece.

D is the induction-coil standing in one corner of the transmitter-case.

The diaphragm 2, circumscribed by its damping-ring of rubber or similar material, rests in a ring-seat, C, affixed to the cover, the necessary vocalizing-chamber being thus formed between the diaphragm and a portion of the 70 cover. The diaphragm is held in place by the clip e and damping-spring s. From opposing points upon the said ring-seat project brackets 16 and 21, and to these, by spring-plates 18 and 24, are hung supporting-blocks 19 and 23. The upper block holds between pieces of insulating material a flat spring, 26, from which depends the compound granulation-holding button a'. In like manner the lower block, 19, sustains, also, between pieces of insulating material, the spring 20, supporting the compound conductor-holding button a. Both springs are insulated from the diaphragm and surrounding elements by their non-conducting clamping-pieces, as well as by the 75 pieces i of non-conducting tubing which surround them. Both springs, with their dependent buttons, are adjustable with reference to one other and to any interposed conductor or electrode by the screws 17 and 22, which, entering the brackets 16 and 21, bear upon the blocks 19 and 23. A bracket, 39, is also affixed to the center of the inner surface of the diaphragm, and has outwardly-projecting arms 4, which adjustably support a cross-rod, 5, ca- 80 85 90 95 100

pable of sliding by sockets 7 upon them, and which, when in its proper place, can be there fixed by screws 8.

About the middle of the rod 5 a small blunt-pointed metal stud, (platinum being preferred) projects both ways and makes contact with the inner conducting face or wall of both compound buttons, the surface of said faces being, if desired, plated or otherwise metallized for the purpose of improving the contact.

As shown in the drawings, each of the buttons *a* has a peculiar construction. Each is formed of a front plate, 12, and a back plate, 10, of carbon, insulated and separated from one another by an elastic intervening ring, 11, of felt or rubber, to which both plates at their edges are affixed, thus forming an inclosed compressible and expandable chamber, within which is placed a quantity of granulated carbon or similar material. It will, however, readily be seen that while such a special button is to be preferred it is not an essential feature, and an ordinary solid button may be employed, if desired. The induction-coil *D* is shown also in diagram in Fig. 2 and has a double primary helix.

One pole of the local battery is connected with the binding-screw 13. This is united by wire *t* to the metal bracket attached to the diaphragm center and the circuit continues therefrom to the cross-bar and metal electrode 36. At this point the circuit bifurcates, one branch leading through the compound button *a*, which has its front plate in contact with the stud of the electrode 36, and by wire *g* to one end of one of the primary helices, through the said helix and back to the other pole of the battery by wire *j* and binding-screw 14. The other branch leads from the electrode 36 through the button *a'*, and then, *via* the suspending spring thereof and the wire *h*, to its own primary helix, and back to the opposite pole of the battery by the wire *j* and the same binding-screw 14. The two terminal ends *f* and *k* of the secondary helix connect, respectively, with the binding-screws 15 and 16, and then to line, or to line and earth.

From the foregoing description it is obvious that the central electrode, 36, is in normal contact with both compound buttons, and this contact must remain permanent and unimpaired. Its pressure upon both is, however, capable of being greatly varied by the vibratory action of the diaphragm, and is, moreover, adjustable by the screws 17 and 22. When, by the condensation of the air-waves within the vocalizing-chamber, the diaphragm makes an inward vibration, the electrode 36 increases its pressure against the button *a*, but the pressure of its contact with *a'* is weakened. Furthermore, inasmuch as each of the said buttons is in itself a complete current-varyer, and is, moreover, mounted on a yielding spring and provided with an elastic annulus between its two faces, the resistance under this action of both buttons is similarly but oppositely and simultaneously varied. We may

assume, therefore, that the resistance both of the button *a* as a whole and of the contact between the said button and the metal point 36 is lowered, and thus that the resistance of the branch *g* of the primary circuit is lowered to a degree representing the sum of these actions; and that the current flowing in the primary circuit, forming the extension of such branch 75 circuit, is in like manner increased to an extent inversely proportional to such depreciation of resistance. And not only so; but the resistance of the button *a'* as a whole and of its contact with the metal electrode 36 is increased by virtue of the lessened pressure between the said electrode and the inner face of said button, which permits the two faces thereof to increase their distance from one another and to weaken the contact of the inner one with the said electrode. The resistance in this branch of the circuit being thus at any given moment increased, the current is in the branch *h* of course decreased. Thus the electrical variations in the secondary coil and main 90 circuit *k f* have a much wider range than is usual, and when the air in the vocalizing-chamber is again rarefied the diaphragm expands outwardly and the foregoing actions are repeated reversely. 95

If simple buttons replace the compound buttons *a* and *a'*, the change in resistance is at the points of contact with the electrode 36 only.

I do not broadly claim as my invention the use, in connection with a double-contact transmitter, of an induction-coil having a differential primary helix, that being claimed by S. W. Robinson in Letters Patent No. 227,653, bearing date May 18, 1880.

Having now described my invention and its 105 operation, I claim—

1. The combination, in a telephone-transmitter, of a vibratory diaphragm, an electrode adjustably mounted thereon and adapted to be vibrated thereby, a pair of compound-button electrodes, each formed as hereinbefore described, and each independently supported upon an adjustable spring, by which the two buttons are maintained in permanent but variable contact with the said diaphragm-electrode, one on each side thereof, and an induction-coil, having a secondary helix, adapted for inclusion in a main circuit, and a double and differentially wound or connected primary helix, each of the said wires being in circuit with one of the compound-buttons, and both with the diaphragm-electrode, substantially as described herein. 115

2. The combination, in a telephone transmitter, of a vibratory diaphragm, an adjustable electrode supported upon a bracket mounted on the center of said diaphragm, two spring-supported compound-button electrodes, arranged to press with permanent but variable contact, one on each side of the said diaphragm-electrode, an adjusting-screw for each of the said buttons, whereby the initial contact-pressure thereof may be varied, and an induction-coil having a double-wire primary helix, the 125 130

two wires of said helix being in circuit each with one of the said compound buttons, and both with a single continuation leading through a battery and through the diaphragm-electrode, whereby the current of said battery is caused to circulate in the two branches of the primary helix in opposite directions, and whereby the said current may, by the vibrations of the diaphragm, be simultaneously increased in one branch and diminished in the

other, and vice versa, substantially as described.

In testimony whereof I have signed my name to this specification, in the presence of two subscribing witnesses, this 3d day of September, 1887.

HAMMOND V. HAYES.
